UNITED STATES PATENT OFFICE.

CARL E. PUTNAM, OF FAIRPORT, NEW YORK, ASSIGNOR TO MARKEM MACHINE COMPANY, OF BOSTON, MASSACHUSETTS, A CORPORATION OF MASSACHUSETTS.

TYPE UNIT.

Application filed January 11, 1926. Serial No. 80,509.

This invention relates to marking or printing machines and particularly to those machines which employ a type chase presenting one or more slotted bars adapted to hold the type and into which the type may be inserted from above. A type chase having this construction is illustrated in co-pending application Serial No. 698,869, filed March 13, 1924, jointly by myself and Fred A. Putnam. In the type chase shown in said application Serial No. 698,869 each type element is made with a body portion of a size to be received in the type-receiving slot, the upper end of the type element being somewhat wider than the body thereby to provide shoulders which rest on the top edge of the slotted type-supporting bar, said shoulders serving to position properly the type.

In order that a type of this character may always function properly and be correctly lined up when inserted in the slot, it is necessary that the supporting shoulders of the type which rest on the top edge of the supporting bar should be of a character to withstand any wear to which the type may be subjected and also to withstand any distortion due to any pressure or strain to which the type is subjected in the printing operation.

Where each type element is an integral shouldered element it is necessary to make each type element of some relatively hard material, such for instance as brass. To make a type element out of such hard material is a rather expensive operation due to the fact that the type characters have to be cut or engraved on the end of the type elements.

It is one purpose of my present invention to provide a novel type member which can be used in a type chase such as above described and which can be manufactured at a considerably less expense than that involved in making the type characters of brass or some other hard material.

This purpose is accomplished herein by using ordinary printer's type, which, as is well known, are of relatively soft metal but are comparatively inexpensive to purchase, and by applying to the end of each type a cap member of some harder material constructed to provide the necessary shoulders to rest on the top of the type-supporting bars. With this construction the body of each type member is of the inexpensive type

metal while the upper part of the type is of the hard material which is adapted to withstand wear and also to hold its shape against distortion when subjected to pressure.

Another feature of my invention relates to a novel construction of type in which the body of the type is made of ordinary commercial type metal type and the upper end of hard metal and in which the supporting shoulders are so arranged that the individual type can be set as close together as ordinary printer's type.

In order to give an understanding of the invention I have illustrated in the drawings a selected embodiment thereof which will now be described after which the novel features will be pointed out in the appended claims.

Fig. 1 is a perspective view of a type element embodying my invention;

Fig. 2 illustrates an ordinary printer's type;

Fig. 3 is a perspective view of the cap member which is applied to the printer's type to make my improved type element;

Fig. 4 is an under side view of a portion of a type chase embodying my invention;

Fig. 5 is a sectional view showing the type chase in a printing head;

Fig. 6 is a section on the line 6—6, Fig. 4.

The type chase herein illustrated and which is similar to that illustrated in co-pending application Serial No. 698,869 comprises a frame 1 having a plurality of slotted type-supporting bars 2, the type being inserted in the slots 3 thereof. Each type-supporting bar is shown as formed from two spaced strips 4 which are connected together at their ends, the spaces between the strips forming the slots 3. This type chase is designed to be used with type members which have a shank portion that extends through the slot 3 and also has shoulders to rest on the top of the strips 4. When the type have been set into the type chase for printing any desired data then the latter is secured to a printing head 5 in some appropriate way.

The type chase has a rib 6 at one edge which engages a lip 7 formed on the printing head 5 and said chase also has another lip 8 at its opposite edge which is engaged by a latch member 9 that is pivoted at 10 to the printing head and is acted on by a spring that normally holds it in its inoperative position in engagement with the lip 8. When

the type chase is in this position the upper ends of the type rest against the bottom of the printing head and the shoulders of the type engage the top of the bars 4, the type thus being held rigidly in place. This construction is described fully in the above-mentioned co-pending application.

In accordance with my present invention each type member is made up of ordinary printer's type such as shown in Fig. 5. Printer's type is a well known article of commerce which can be freely purchased on the market and which is made with type character in a variety of designs. A printer's type such as purchased on the market, one of which is illustrated at 12 in Fig. 2, is not suitable for use in the type chase herein shown because it lacks the supporting shoulders to rest on the top of the slotted bars 2. 20 In order to adapt this printer's type for use in the above-mentioned type chase I provide each element 12 with a cap member 13 of some relatively hard metal, such as brass, and which forms the desired shoulders. The 25 cap member herein shown has a general U-shape and is provided with a socket 14 between the arms thereof into which the upper end of the type member 12 is fitted. This socket 14 may conveniently be dove-tailed so 30 as to form something of an interlocking engagement between the cap and the type.

The shoulders for supporting the type are formed by the lower ends 15 of the arms of the cap member, said arms being of the right 35 length for this purpose. Inasmuch as the printer's type are of a standard length it will be necessary to cut off the upper end of each type, as indicated at the dotted lines 16, Fig. 2, the amount which is cut off being 40 equal to the thickness of the bridge portion 17 of the metal cap, so that when the cap is applied to the type it will have the same length it originally had. This makes a type element such as shown in Fig. 1 and which presents 45 a body portion of type metal having the type character 18 at its end, and also having shoulders 15 of some harder material than the type metal and which are adapted to rest on the top of the slotted bars 2. The 50 upper end or top surface 19 of the type character which rests against the bottom of the printing head is also of relatively hard metal.

Inasmuch as the caps 13 are of the same thickness as the type in the direction of the 55 length of the line of type it is possible to set my improved type characters as closely together as ordinary printer's type can be set. Ordinary printer's type can be converted into a type element embodying my 60 invention at a relatively small expense and when so converted they may be used for setting up lines of type in the type chase with as great facility as type characters illustrated in the above-mentioned application. 65 The cost of the type elements herein shown is, however, very much less than that of the brass type elements illustrated in the above-mentioned application.

While I have described herein a selected 70 embodiment of my invention I do not wish to be limited to the constructional features shown.

I claim:

1. A type element comprising a body portion of ordinary printer's type and a cap member of material harder than type metal which encloses the upper end of the type 75 and forms supporting shoulders.

2. A type member for use in a type chase 80 having a slotted type-holding bar, said type member comprising printer's type and a cap member of material harder than the printer's type applied to the end thereof and forming shoulders to rest on the top of the 85 slotted bar.

3. A type member for use in a type chase having a slotted type-holding bar, said type member comprising printer's type of type metal, and a U-shaped cap of metal harder 90 than the type enclosing the upper end thereof and forming shoulders to rest on the top of the type-supporting bar.

4. A type member for use in a type chase having a slotted type-supporting bar, said 95 member being formed of printer's type and a U-shaped cap member of material harder than type material fitting the upper end of said type member, the ends of the arms of the cap member forming shoulders to rest on the top of the type bars, and said member having the same dimension as said type members in the direction of the line of type. 100

In testimony whereof, I have signed my name to this specification.

CARL E. PUTNAM.
